UNITED STATES PATENT OFFICE.

HJALMAR PAINE, OSCAR A. WIDERBERG, AND PAUL R. JOHNSON, OF WORCESTER,
MASSACHUSETTS.

CUSHION-TIRE.

1,201,495.

Specification of Letters Patent.

Patented Oct. 17, 1916.

Application filed April 6, 1916. Serial No. 89,454.

To all whom it may concern:

Be it known that we, HJALMAR PAINE, OSCAR A. WIDERBERG, and PAUL R. JOHNSON, said PAINE being a subject of the Czar of 5 Russia, and said WIDERBERG and said JOHNSON being citizens of the United States, residing at Worcester, in the county of Worcester and State of Massachusetts, have invented, a new and useful Cushion-Tire, of 10 which the following is a specification.

This invention relates to vehicle tires of the cushion type in which in place of the usual pneumatic inner tube a system of springs are employed for accomplishing 15 similar purposes.

The principal objects of the invention are to provide a tire of this type with springs so constructed that they can be readily assembled and also taken out individually and 20 replaced in case of breakage; also to provide a double system of springs, the second set assisting in taking the pressure when there is too much for the first series to stand themselves; also to provide improvements in the 25 springs themselves and in the means for holding them and removing them, and an improved rim.

Further objects and advantages of the invention will appear hereinafter.

Reference is to be had to the accompanying drawings, in which—

Figure 1 is a side view of a portion of a tire constructed in accordance with this invention and partially broken away to show 35 interior construction; Fig. 2 is a sectional view of the same on the line 2—2 of Fig. 1; Fig. 3 is a central sectional view of one of the holding blocks taken on a plane parallel with the plane of section of Fig. 2; Fig. 4 is 40 a central sectional view in a plane at right angles to the same; Fig. 5 is a side view of a key for use in removing the blocks, and Fig. 6 is an end view of the same.

The invention is shown as applied to a 45 wheel having the usual felly 10 and provided with a metallic rim 11. This rim in the present case is shown as provided with a series of projections 12; a continuous clamping ring 13 is provided, resting at the inner 50 edge on projections 12 and having a clamping jaw at the outer edge for engaging the bead of the outer casing 14 of the tire. This clamping ring is held in position by bolts 15 and nuts. It will be seen that on account of 55 the relative location of the parts this ring

has fulcrums at 12 and is capable of being tightened up to any desired degree.

The outer casing can be made in any of the usual ways, but we have shown a layer of leather 16 on the inside to receive the action of the springs within as will appear. It will be understood, however, that any desired style of flexible outer casing can be used.

When the parts are assembled a plurality 65 of blocks 20 are arranged around the rim. Each one of these blocks is provided with two sockets 21 at the top or outer surface, these depressions being symmetrically arranged and of substantially circular section 70 at their ends and communicating with each other at the center. The sides of these blocks also have concave sockets 22 extending from one edge of the block nearly to the other for a purpose which will appear. Through the 75 block longitudinally extends a passage 23 which is circular at the center and has two opposite narrow extensions as 24. This block is provided with legs 25 caused by coring out the same between the sides. 80 These blocks are arranged to have their opposite surfaces converge slightly so that they can be arranged around the rim, as indicated in Fig. 1. They are held in their relative positions by a series of horse-shoe springs 85 30. Each of these springs has its opposite ends 31 curved, but preferably in a substantially circular form to engage in the sockets 21. Each spring is arranged to engage two adjacent blocks and help hold them in position. The springs may, if desired, come into contact with each other or substantially so at their widest parts, and they extend around the rim in the plane of the wheel.

An additional series of springs 35 is 95 shown shaped substantially like the springs 30 and having circular ends 36 adapted to enter the sockets 22. These springs are designed to engage in the opposite sockets of a single block and to partake of the interior 100 shape of the casing, extending around the same inside transversely. They are thus held at their curved ends in these sockets and substantially engage the inner surface of the outer casing throughout their length so that 105 they always partake of the motions thereof, and their natural resiliency resists all motions inwardly of all parts of this casing. They thus receive the pressure directly and as the opposite ends of each spring are re- 110

ceived in opposite sides of the same block each spring is acted on uniformly from end to end. They are assembled by moving them into the sockets edgewise.

5 It will be seen that only the springs 30 hold the blocks in position. They also act in assisting to take the weight if the outer casing is forced inwardly far enough for these springs 30 to come in contact with the 10 springs 35 at the outer circumference. In this way a double spring action is secured, because under great strains there is a second series of springs ready to take part of the burden and assist in holding the casing 15 nearly in its normal position.

A very important feature of this invention lies in the fact that the parts are easily assembled and that when it is desired to take out a block on account of the breakage of 20 a spring 35 it can be done very readily. It is for this purpose that the passage 23-24 is provided and in connection with that passage we use a key 26. This key is provided with a transverse bar 27 near its end adapted 25 to pass through the flat passage 24 while the shank of the key passes through the round passage 23. In order to hold the blocks in position when the key is used for pressing the springs out of the sockets 21, a 30 block 37 is used having a flat bar 38 adapted to enter a large key slot 39 in the end of the block. When it is desired to remove a block this block and key are inserted through the 35 passages and turned. The ends of the bar 27 come into contact with the ends of the the two springs 30 which engage that block and force them out of the sockets 21. The free end of each spring 30 then springs back 40 against the next block. The block 37 is held in the other hand to prevent the block 20 moving in with the spring. This having been accomplished, the key is turned so that the bar 27 will not pass through the passage 24, and then the block 20 is pulled out by 45 means of the block 37. The blocks 20 are spaced apart so that they can be moved circumferentially away from a broken spring 35 in opposite directions to provide a material space for removing and replacing it. 50 The springs 30 tend to close together at their ends and assist in moving two blocks apart that have been disconnected. When a block has been inserted the ends of the adjacent 55 springs 30 will either be located in the sockets or on the outer edges of the block. In the latter case a flat plate or screw driver can be inserted between the blocks and the ends of the spring pushed in toward the center of the block when they will engage in the 60 sockets. The broken spring can be removed readily and a new one substituted for it, and the casing spread so that the block 20 can be replaced.

Although we have illustrated and described only a single form of the invention

we are aware of the fact that modifications can be made therein by any person skilled in the art without departing from the scope of the invention as expressed in the claims. Therefore we do not wish to be limited to all 70 the details of construction herein shown and described but

What we do claim is:-

1. In a tire, the combination of an outer flexible casing, and a series of blocks arranged circumferentially therein, of a plurality of substantially horse-shoe shaped springs located in said casing in the plane of the tire and having their free ends extending toward the center, the two free 80 ends of each spring engaging two adjacent blocks and holding them in position.

2. In a tire, the combination of a flexible outer casing, a plurality of blocks arranged therein, each of said blocks having two 85 sockets in the outer surface thereof, and a plurality of springs arranged within said casing, the two ends of each spring entering the sockets in different blocks, the resiliency of said springs acting to hold the 90 blocks in position.

3. In a tire, the combination of a flexible outer casing, of a plurality of blocks arranged therein out of contact with each other, each of said blocks having two symmetrically arranged sockets in the outer surface thereof, and a plurality of springs arranged within said casing having curved free ends entering said sockets in different blocks, the resiliency of said springs acting 100 to hold the blocks in position, said springs being arranged in the plane of the wheel and substantially contacting with each other at their points of greatest width and being normally out of contact with the inner surface 105 of said casing.

4. In a tire, the combination of a flexible outer casing, of a plurality of blocks arranged therein out of contact with each other, each of said blocks having two symmetrically arranged sockets in the outer surface thereof, and a plurality of springs arranged within said casing having curved free ends each entering one of said sockets of adjacent blocks, the resiliency of said 115 springs acting to hold the blocks in position, said springs being arranged in the plane of the wheel and substantially contacting with each other at their points of greatest width and being normally out of contact with the 120 inner surface of said casing, and an additional series of springs arranged transversely to the first named springs and each one being held at its ends by one of said blocks.

5. In a tire, the combination of a flexible outer casing, of a plurality of blocks arranged therein, and a plurality of springs arranged within said casing, the two ends of each spring engaging different blocks, and 125

an additional series of springs arranged transversely to the first named springs and each one being held at its ends by one of said blocks and contacting with the inner surface 5 of the casing substantially throughout its length.

6. In a tire, the combination of a flexible outer casing with a series of blocks arranged therein, yielding means for holding 10 said blocks apart, said blocks each having sockets in their opposite sides, and a series of springs contacting with the inner surface of said casing and having their ends bent up and entering said sockets so as to be held 15 thereby.

7. In a tire, the combination of a flexible outer casing with a series of blocks arranged therein, a series of springs for holding 20 said blocks in position, said springs being arranged all in the same plane and in the plane of the wheel, and being adapted to hold the blocks yieldingly in position, said springs being normally out of contact with

the inner surface of said casing, and an additional series of springs transversely arranged and held at their inner ends by said 25 blocks and located outside the first named springs whereby the last named springs constantly tend to hold the casing in its expanded position, and the first named springs 30 will assist that action when the casing is contracted to a certain position.

8. In a tire, the combination of a flexible outer casing with a series of blocks arranged therein, said blocks each having sockets in 35 one end and having a key slot therethrough to said sockets, and a series of springs having their ends entering said sockets and in position to be displaced by the key when inserted.

In testimony whereof we have hereunto set 40 our hands.

HJALMAR PAYNE.
OSCAR A. WIDERBERG.
PAUL R. JOHNSON.
